Inventor,
Nelson E. Funk,
By his Attorney,
Henry J. Luecke.

UNITED STATES PATENT OFFICE.

NELSON E. FUNK, OF MONTCLAIR, NEW JERSEY.

VARIABLE TURNING BAR.

Application filed February 19, 1925. Serial No. 10,197.

This invention relates to adjustable turning bars.

An object of this invention is to provide a positively adjustable form of turning bar for printing presses and the like co-ordinated with folding and like supplemental machines for regulating the path of travel of the paper web.

In presses for newspaper printing and like impression operations, it has been found desirable to locate the folding machines and like co-ordinated machines at an angle to the direction of travel of the web of the paper. It has been heretofore proposed to turn the course of travel of the paper web by means of a bar arranged angularly with respect to the path of travel of the paper web from the printing or other press. However, in such prior proposals, such turning bar is not adjustably mounted nor co-ordinated with the alignment of the plates or equivalent of the printing or other units, and accordingly the absence of nicety of adjustment of such turning bar has introduced the condition of non-registry of the paper web relative to the printing or other plates or the condition of non-registry of superimposed impressions on the paper web, or both of such defects.

Pursuant to the preferred form of my invention, the turning bar is mounted on a frame unitarily with or directly attached to the frame of the printing or other press, such turning bar being supported at a predetermined angle to the direction of travel of the paper web through the printing or other press and usually at an angle of forty-five degrees, such disposition being attained by providing for one end of the turning bar a substantially freely slidable support and providing at the opposite end of the turning bar a slidable support coupled with a rack coacting with a key carried by or to be inserted within a suitable housing of the sliding support, such key and such rack providing for the sliding of the turning bar to any desired adjusted position with the most exacting degree as may be desired.

Further features and objects of the invention will be more fully understood from the following detailed description and the accompanying drawings, in which

Fig. 1 is a top plan view showing one form of turning bar embodying my invention;

Fig. 2 is an elevation on section line 2—2 of Fig. 1;

Fig. 3 is a detail, top plan view of one

form of housing for the slidable support for one end of the turning bar;

Fig. 4 is an end view of Fig. 3;

Fig. 5 is an elevation taken on section line 5—5 of Fig. 3;

Fig. 6 is an elevation taken on section line 6—6 of Fig. 3;

Fig. 7 is a detail, end view of the key shown in Fig. 6; and

Fig. 8 is an elevation of the key shown in Fig. 7.

Referring to Figs. 1 and 2, the embodiment of my invention as illustrated in the drawings comprises the turning bar 10 adjustably mounted as is set forth more particularly hereinafter relative to the oppositely disposed, side frames 11, 12. Such side frames 11, 12 may extend unitarily of the frame of the printing press or other impression machine or may be attached thereto. The web of the paper delivered from the printing press or other impression machine is indicated at 13 and its direction of travel by the arrow 14. In the particular form of the invention illustrated in the drawings, the turning bar 10 is disposed at substantially the angle of forty-five degrees to the general direction of travel of the paper web 13 indicated by the arrow 14, and accordingly the passage of the web subsequent to its transit about the turning bar 10 is substantially at right angles to its previous travel. The subsequent travel of the paper web is indicated at 15 and its direction by the arrow 16.

To attain the aforesaid and similar results, the turning bar 10 is provided with parallel sliding supports. One sliding support 17 may be in the form of a round bar, extending from and secured at its opposite ends to the side frames 11, 12 by means of the tapped bolts, 18, 19. The end 20 of the turning bar 10 is pivotally carried by the sliding block 21, provided with the opening 22 for slidingly receiving the bar 17. Such pivotal mounting may be by means of the headed pins 23, tapped screw or the like, freely passing through the smooth opening 24 in the end 20 of the turning bar 10, and tapped at its lower threaded portion 25 in the correspondingly threaded opening 26 of the sliding block 21. The head of the bolt 23 is preferably countersunk below the surface of the turning bar 10, as is indicated by the provision of the enlarged opening 27. Preferably, the block 21 is formed to afford

ready setting in any desired adjusted position, which result is attained by splitting the block 21 as is indicated at 28, see Fig. 2, and providing the transverse smooth opening 29 and threaded opening 30 for receiving the bolt 31 threaded at its end portion 32.

At the opposite end 33 of the turning bar 10, I provide a slide housing 34 to which the end portion 33 of the turning bar 10 is rigidly secured, as by means of the screws 35, 36 tapped within the openings 35^a, 36^a, see Fig. 2, in the slide block 34. The screws 35, 36 are preferably countersunk below the surface of the turning bar 10.

Coacting with the slide housing 34, I provide the bar 37 extending from and between the oppositely disposed side frames 11, 12 and secured thereto by the tapped bolts 18^a, 19^a. The bar 37 may be received within the opening 38 of the slide housing 34. I further provide the rack 39 which may be applied to or machined integrally of the slide bar 37. For adjustment of the setting of the slide housing 34 relative to its slide support 37 for the end 33 of the turning bar 10 and the consequent adjustment of its opposite end 20 of the turning bar 10 relative to its sliding support 17, I provide a key 40 coacting with the slide housing 34 for accurately positioning the slide housing 34 relative to its slide support 37. Such key 40 may be of the removable type as is indicated in the illustrations of the drawing, in which form the key 40, see Figs. 6 and 8, has body portion 40^a of true cylindrical form and its end portion 40^b machined to provide the longitudinally extending spurs 41 or spaced teeth extending in uniform spacial relation to one another corresponding to the uniform spacing of the teeth of the rack 39. It will be noted from Fig. 7, that the outer periphery of the spurs or teeth 41 may coincide or be slightly less than the periphery of the body portion 40^a of the key 40. The pin 42 extends through an opening at the opposite end of the key 40, to facilitate turning of the key manually or otherwise.

Such key 40 is arranged to be inserted within the recess 43, see Figs. 3, 4 and 5, for affording access of the spurs or teeth 41 of the key 40 to the teeth of the rack 39. Such recess 43 is substantially cylindrical and but slightly larger in diameter than the diameter of the body portion 40^a of the key 40, to provide self-centering of the key 40 when it is being turned. It will be observed from Fig. 4, that the recess 43 communicates at the location indicated at 44 with the opening 38 through which the slide bar 37 passes.

In the aforesaid specific embodiment, as will be noted from Fig. 1, the key 40 is inserted within the opening 43 by pushing the key upwardly, which embodiment of my invention is convenient when the key 40 is re-

movable from its slide housing 34, but it will be understood that the location of the opening 43 may be varied as desired.

Upon turning the key 40 in the proper direction, with the tightening bolt 31 of the slide block 20 loosened, it will be perceived that the slide housing 34 is adjusted accurately in its setting relative to its slide support 37 and by virtue of the rigid connection of the end portion 33 of the turning bar 10 relative to the slide housing 34, the turning bar 10 as a whole is displaced for all setting parallel to itself and the opposite end portion 20 of the turning portion 10 is, accurately moved and without any binding engagement relative to its slide support 17. Upon attaining the desired adjusted setting, the tightening bolt 31 of the slide block 21 is then tightened, to thereby lock the casing 21 and therewith the end 20 of the turning bar 10 at any desired position relative to the sliding support 17.

Preferably, the slide housing 34 is also provided with tightening means, as by slotting the slide housing 34 as is indicated at 45, see Figs. 2 and 4, and by providing the smooth recess 46 and threaded recess 47, which recesses 46, 47 extend transversely to the slot 45, and receiving the tightening bolt 48, corresponding to the aforesaid tightening bolt 31, to thereby lock the casing 34 and therewith the end 33 of the turning bar 10 at any desired position relative to the sliding support 37.

From the above particulars of the embodiment of my invention illustrated in the drawings, the operation of the parts of the aforesaid embodiment will be understood, and variations of form and modifications of the aforesaid parts for attaining the results of my invention may be made.

By the provision of my invention, the path of travel of the web 13 of paper or the like and the edges of the paper web 13 relative to the printing plates on the cylinders of the press or equivalent impression means will be shifted in either direction substantially at right angles to the direction represented by the arrow 14, and thereby rectifying accurately and without disturbance of the printing cylinder or the plates thereon the path of travel of the paper web through the press from the point of unwinding of the roll of paper web, which is usually mounted at the opposite end of the press. By the adjustment afforded by my invention, the accurate registration of successively applied superimposed impressions on the paper web may be had in a most ready manner.

It will be understood that the paper web 13 bearing the desired printing or other impression after passage about the turning bar 10 is led to the folding unit or other accessory or other attachment for subsequent

operations as may be desired. The free passage of the paper web 13 above and below the turning bar 10 is afforded by the spacing of the slide supports 17, 37 for the opposite ends 20, 33 of the turning bar 10.

In lieu of a rack, any other suitable device having uniformly spaced teeth or equivalent elements may be employed and the key provided with corresponding teeth or like uniformly spaced elements; it will also be perceived that the key 40 may be arranged to be held permanently in position.

Whereas I have described my invention by reference to specific forms thereof, it will be understood that many changes and modifications may be made without departing from the spirit of the invention.

I claim:

1. In a web printing press, a turning bar for the paper web, a support for slidably mounting one end of said turning bar, a second support spaced from said first-named support and slidably mounting the opposite end of said turning bar, a rack carried by one of said supports, a casing carried by said turning bar and provided with an opening and a pinion rotatably received within said opening and coacting with said rack to adjustably position the two ends of said turning bar simultaneously relative to said two supports respectively.

2. In a web printing press, a turning bar for the paper web, a support for slidably mounting one end of said turning bar, means for locking said one end of said turning bar at will at any desired position relative to said support, a second support spaced from said first-named support and slidably mounting the opposite end of said turning bar, a rack carried by one of said supports, a casing carried by said turning bar and provided with an opening and a pinion rotatably received within said opening and coacting with said rack to adjustably position the two ends of said turning bar simultaneously relative to said two supports respectively.

3. In a web printing press, a turning bar for the paper web, a support for slidably mounting one end of said turning bar, means for locking said one end of said turning bar at will at any desired position relative to

said support, a second support spaced from said first-named support and slidably mounting the opposite end of said turning bar, a rack carried by one of said supports, a casing carried by said turning bar and provided with an opening, means for locking said opposite end of said turning bar at will at any desired position relative to said second-named support and a pinion rotatably received within said opening and coacting with said rack to adjustably position the two ends of said turning bar simultaneously relative to said two supports respectively.

4. In a web printing press, a turning bar for the paper web, a support for slidably mounting one end of said turning bar, means for locking said one end of said turning bar at will at any desired position relative to said support, a second support spaced from said first-named support and slidably mounting the opposite end of said turning bar, a rack carried by one of said supports, a casing carried by said turning bar and provided with an opening and a pinion rotatably and removably received within said opening and coacting with said rack to adjustably position the two ends of said turning bar simultaneously relative to said two supports respectively.

5. In a web printing press, a turning bar for the paper web, a support for slidably mounting one end of said turning bar, means for locking said one end of said turning bar at will at any desired position relative to said support, a second support spaced from said first-named support and slidably mounting the opposite end of said turning bar, a rack carried by one of said supports, a casing carried by said turning bar and provided with an opening, means for locking said opposite end of said turning bar at will at any desired position relative to said second-named support and a pinion rotatably and removably received within said opening and coacting with said rack to adjustably position the two ends of said turning bar simultaneously relative to said two supports respectively.

In testimony whereof I have signed this specification this 13th day of February 1925.

NELSON E. FUNK.
